UNITED STATES PATENT OFFICE.

ISIDORE NEFT AND HUGH P. NASS, OF SEATTLE, WASHINGTON.

PROTECTIVE CURTAIN.

Application filed June 27, 1921. Serial No. 480,857.

To all whom it may concern:

Be it known that we, ISIDORE NEFT and HUGH P. NASS, citizens of the United States, residing at Seattle, in the county of King and State of Washington, have invented certain new and useful Improvements in Protective Curtains, of which the following is a specification.

This invention relates to protective curtains for display windows, show cases, and the like, and it comprises a foldable curtain, means for opening said curtain to operative position, control means to normally maintain said curtain in folded position, said 10 control means being rendered inoperative by the breaking of the window to permit said curtain to assume an opened position, and means for locking said curtain when opened.

In the present invention, we have provided a theft preventing device adapted to be arranged on store windows, such as windows of jewelry stores or windows of any sort in which valuable articles are displayed. The device may also be applied to show cases 25 and other glass containers.

The invention comprises a screen or curtain made of suitable material adapted to be folded at the top or one side of the window under normal conditions. A weight or other suitable means is provided for the purpose of opening the curtain when released. The tendency of the weight to open the curtain is normally overcome by suitable control means, such as an electro-magnet normally energized to maintain the weight in 30 raised position. When the magnet is de-energized, the weight lowers the curtain adjacent the glass and an automatic locking device is employed for the purpose of immediately locking the curtain in front of the opening made by breaking the window.

While any suitable type of control means may be employed, we have found that a magnet arranged in circuit with an electric conductor extending around the window whereby it will be broken to break the circuit when the window is broken is highly advantageous.

In connection with the foldable curtain, an audible signal may be employed, the signal being arranged in circuit normally open and closed by the opening of the curtain to sound an alarm.

In the accompanying drawings, we have shown several embodiments of the invention. 55 In this showing:

Figure 1 is a front elevation of one form of the invention,

Figure 2 is a detail view of a portion of 60 the curtain,

Figure 3 is a vertical sectional view,

Figure 4 is a diagrammatic view of the electric circuits, and

Figure 5 is a front elevation showing a 65 slightly different form of curtain,

Referring to the drawings, the reference numeral 1 designates the glass which may be the window of a store, the front of a show case, or a portion of any other display case employed for holding articles of value. As 70 shown, the glass is mounted in a suitable frame 2. A curtain 3 is secured to a suitable supporting member 4, arranged at the top of the window, the curtain being made of canvas or other suitable 75 material and being foldable. As shown, a frame comprising sections of wire 5, hinged-ly secured to each other as at 6' may be attached to the curtain to prevent a thief from cutting through the curtain when in operative position. A bar 6, having a weight 7 attached thereto, is secured to the bottom of the curtain, and this weight is adapted to normally hold the curtain in open position, as illustrated in Figure 1. The curtain is 80 maintained in folded position by means of an electro-magnet 8, which when energized, attracts the bar 6 with sufficient force to overcome the force of gravity. It will be apparent that when the magnet is deener- 85 gized, the weight 7 will cause the curtain to lower and close the window space. The bar 6 is provided with a plurality of teeth 9 which, when in lowered position, are adapted to cooperate with a catch 10, pivotally 90 mounted below the window frame, as at 11, and provided with a spring 12 and normally maintaining it in forward position. A suitable handle 13 is provided to permit the teeth 9 to be disengaged from the catch 10. 100

Means are provided for opening the circuit through the electro-magnet 8 when the window is broken. Referring to Figures 1 to 4 of the drawings, the electro-magnet is connected to a source of current 105 14 by a suitable connection 15. The oppo-

site pole of said source of current is provided with a lead wire 16, connected to a branch wire 17. The branch wire is connected to a suitable conductor 18, arranged in the window frame (see Figure 1). The conductor 18 extends around the window frame and the opposite end is connected to the electro-magnet by a connection 19. It will be apparent that when the conductor 18 is broken, as illustrated in Figure 1 of the drawings, the circuit through the magnet will be interrupted. A suitable switch 20 may be provided in one of the connections to the source of current, to permit the device to be rendered inoperative when desired, as when the store is open. The curtain is then retained in raised position by any suitable means (not shown).

Means are provided for giving an audible signal when the curtain is opened to operative position to inform watchmen or policemen that an attempt at robbery is taking place. As shown, the lead wire 15 from the source of current is connected to a bell or other signal device 21. The bell is connected to a contact member 22 by a connection 23. This contact member is adapted to contact with a pivoted contact member 24, connected to the other lead wire 16 from the source of current. As shown, in Figure 3 of the drawings, the pivoted contact member 24 is provided with an extension 25, adapted to be engaged by the curtain when the curtain is in folded position to space the contacts 22 and 24. When the curtain is moved to open position, the contact 24 is caused to engage the contact 22 by suitable spring 26, thus closing the circuit through the bell.

40 In the form of the invention shown in Figure 5 of the drawings, the construction and operation is essentially the same except that the curtain 27 is fan shaped, and is arranged at the side of the window when in closed position. The magnet 8 is arranged at the upper end of the curtain and the curtain is pivotally mounted at the bottom of the window, as at 28. When the magnet is deenergized, the curtain opens across the window. The teeth 9 of the bar 6 are carried near the upper corner of the curtain which, when in open position will be arranged at the bottom of the window opposite the pivot.

55 The operation of the device will be apparent from the foregoing description. When the glass 1 is broken, the circuit through the electro-magnet 8 is interrupted and the magnet deenergized. The force of gravity acting on the rod 6 and the weight

7 causes the curtain to immediately lower to the position shown in Figure 1 of the drawings, and indicated in dotted lines in Figure 3 of the drawings, preventing the thief from gaining access to the interior of the window. As the curtain lowers, one of the teeth 9 is automatically engaged by the catch 10 to retain the curtain in closed position. The provision of the wire framework 5 prevents the thief from cutting an opening through the curtain sufficiently large to gain access to the interior of the window.

When the signal 21 is employed, the opening of the curtain closes the contacts 22 and 24, and an alarm is sounded to notify a watchman or policeman that a robbery is being attempted.

It is to be understood that the forms of our invention herewith shown and described are to be taken as preferred examples of the same, and that various changes in the shape, size, and arrangement of parts may be resorted to without departing from the spirit of our invention or the scope of the subjoined claims.

Having thus described our invention, we claim:

1. In a protective device for show windows, a foldable curtain having one end secured above the window, a bar secured to the free end of said curtain, an electro-magnet arranged above said window adapted to attract said bar when energized to retain the curtain in a raised position, a weight carried by said bar and adapted to lower the curtain when the magnet is deenergized, and means for locking said curtain in lowered position.

2. A protective device for show windows, comprising a foldable curtain having one end secured above the window, a bar connected to the free end of said curtain, an electro-magnet arranged above said window adapted to attract said bar when energized to hold said curtain in raised position, a weight carried by said bar and adapted to lower said curtain when the magnet is deenergized, said bar being provided with a plurality of teeth, and a pivoted catch arranged at the bottom of said window adapted to engage one of said teeth to retain the curtain in lowered position.

In testimony whereof we affix our signatures in presence of two witnesses:

ISIDORE NEFT.
HUGH P. NASS.
